UNITED STATES PATENT OFFICE.

HERBERT S. VALENTINE, OF READING, PENNSYLVANIA, ASSIGNOR TO READING CRANE AND HOIST WORKS, OF READING, PENNSYLVANIA.

BRAKE MECHANISM.

1,114,317.

Specification of Letters Patent.

Patented Oct. 20, 1914.

Application filed May 6, 1913. Serial No. 765,771.

To all whom it may concern:

Be it known that I, HERBERT S. VALENTINE, a citizen of the United States, residing at Reading, in the county of Berks and State of Pennsylvania, have invented certain new and useful Improvements in Brake Mechanism, of which the following is a specification.

My present invention relates to improvements in brake operating mechanisms and it is intended more particularly for use in connection with electric trolley hoists of the character described and illustrated in Letters Patent No. 1,058,497, granted to me on

15 April 8th, 1913.

The object of the invention is to provide a simple and effective mechanism for operating the brake on a motor used in connection with hoists such as described in the above 20 noted patent, whereby, the operation of a hand wheel in either direction will, through the medium of the correlated parts, apply the brake.

My invention further comprehends all of 25 the various novel features of construction and arrangement hereinafter more definitely described.

In the accompanying drawings, the figure 30 is a side elevational view of an electric hoist conveniently embodying my invention.

In said figure the elevated tramway is formed of the I-beam 5, whose lower laterally extending flanges 6 and 7 conveniently provide suitable tracks for the wheels 8 and 35 9 of the traction carriage 10, which is provided with suitable trolleys 12 and 14 for collecting electric current from the stationary conductors 15 and 16, extending parallel with the I-beam 5, and respectively disposed 40 upon opposite sides thereof.

The trolleys 12 and 14 are respectively mounted in a harp 18 carried by a plunger 19, which is mounted to reciprocate in a frame 20 and normally pressed into engagement 45 with the electric conductors 15 and 16 by the spring 21 bearing against a collar 22 on said plunger.

The carriage 10 is provided with forwardly extended frames 24 and 25, to which the transversely extending horizontal supporting plate 26 is secured. Said plate 26 provides a convenient support for the electric motor 28, whose armature shaft 29 carries a pinion 30 in toothed engagement with 50 the gear 31 on the countershaft 32, which is

journaled in bearings 33 in the frames 24 and 25, and which carries the gears 34 and 35 in toothed engagement with the gears 36 and 37 forming the flanges of the forward wheels 8 and 9 of the carriage. The supporting plate 26 is extended toward the left and provides a convenient support for the automatic brake, which comprises the opposed jaws 38 and 39 pivotally suspended from the bearing block 42, which is secured 60 to the plate 26 by bolts. The jaws 38 and 39 are provided with a facing of leather 40, or other suitable material, and embrace the brake drum 41 which is carried by the shaft 29. Said jaws are provided near their free 65 ends with spring cups 43 for the springs 44 and 45, whose tension may be conveniently varied by the bolt 46, which is threaded on its opposite ends and extends through said cup 43 and springs 44 and 45, and is provided with nuts 47 and 48 and washers 49 and 50 bearing against the outer ends of the respective springs 44 and 45.

From the bearing block 42 depends a supporting post 51, carrying at its lower end a bearing 52 for the rock-shaft 53 which carries at one end a centrally pivoted lever 54 whose oppositely extending arms are respectively connected by links 55 and 56 with the free extremities of the jaws 38 and 39. 85 The other end of said rock-shaft 53 carries a lever 57, the free end of which is connected by the link 58 to the yoke-plate 59, which is maintained in proper alignment with the plane of the axis of the controller shaft 60 90 of the controller 61 by the slot 62 in said plate 59, through which said shaft 60 extends. Said yoke-plate 59 is substantially triangular and carries rollers 63 and 64, disposed upon opposite sides of the plane of 95 the major axis of the slot 62, and arranged to traverse the edge of the cam 65, which is mounted on the end of the controller shaft 60 and arranged to be rotated therewith when the controller is actuated to direct 100 electric current from the electric conductors through the motor 28 for propelling the carriage 10. It may be here noted that any rotation of the cam 65 in either direction of rotation will instantly effect a movement of 105 the yoke-plate 59 upwardly, together with the parts connected therewith, and consequently effect the positive mechanical release of the brake, at the same time or slightly before the contacts of the controller, 110

which may be of any well known construction, have closed the circuit.

The means for simultaneously effecting the actuation of the controller and brake releasing mechanism comprises a miter gear 66 on the shaft 60, in toothed engagement with the miter gear 67 on the shaft 68, which is journaled in the bearing frame 70, attached to the controller casing, and which 10 carries the bifurcated head 71, to which is pivotally connected the bifurcated head 72 on the shaft 73 of the hand operating wheel 74 by the link 75, the pintle 76, which connects said link to the head 71 being disposed 15 in a plane normal to the plane of the pintle 77 which connects said link to the head 72.

It will be obvious that the construction thus described affords a universal joint connection between the controlling hand-wheel 20 and the shaft of the controller, whereby the operator may actuate said controller and release the brake from whatever position it may be most convenient for him to cause the hand-wheel to assume. The casing 78 of 25 the hoisting mechanism is suspended from the carriage 10 by the side plates 79, which are connected therewith by the brackets 81, and which provide a suitable support for the resistance box 83.

30 The drum shaft 84 is suitably journaled in the casing 78, and carries the winding drums 85 and 86 upon respectively opposite sides of the casing 78. Said drums are arranged to raise and lower the lifting hook 87, which 35 is pivoted to the block 88 through which the rope or cable 89 loosely extends, with its opposite ends wound around and secured to the respective drums. It will be obvious that when either shaft is rotated from its 40 normally inoperative position shown in the drawings, for instance, in a clockwise direction, the left hand extended end 98 of the spring 94 will be retained by the pin 96,

while the right hand extended end 99 of said spring will be carried around by the 45 pin 95, the rotation being limited by the edge 100 of the projection engaging the pin 93, the tension of the spring 94 being sufficient to return the shaft to its normal position when released. 50

My invention is particularly advantageous in that the automatic brake for the propelling motor of the carriage being manually released by mechanically actuated mechanism, instead of by electric power, 55 said motor may be freed and the carriage shifted even though the electrical conductor be dead.

Having thus described my invention, I 60 claim:

In a brake operating mechanism, a lever, means for actuating said lever comprising a yoke plate, a link connecting the free end of the lever with the yoke plate, a horizontal shaft passing through the yoke plate, a cam 65 carried by said shaft and rotatable therewith, a pair of rollers carried by the yoke plate and arranged to traverse the edge of the cam, and means for rotating said shaft including a miter gear on the shaft, a vertical shaft, a miter gear on the vertical shaft 70 in mesh with the gear on the horizontal shaft, a head piece carried by the vertical shaft, a hand-wheel shaft, a head piece carried by the hand-wheel shaft, a link connecting said head pieces, and a wheel on 75 the hand-wheel shaft, whereby rotation of said wheel in either direction will actuate the brake mechanism.

In testimony whereof I affix my signature 80 in presence of two witnesses.

HERBERT S. VALENTINE.
